EDGE ROLL DEVICE

Arthur Dean Smith, San Lorenzo, Calif., assignor to Kaiser Aluminum & Chemical Corporation, Oakland, Calif., a corporation of Delaware

Application March 2, 1953, Serial No. 339,794

17 Claims. (Cl. 80—31.1)

This invention relates to rolling mill devices. More particularly it is concerned with a vertical edging mill, which may be used to roll the side edges of metallic ingots or slabs prior to their entry into a main stand of horizontally mounted rolls in a rolling mill and the providing of novel means for operating and actuating the edge rolls of the edging mill.

In normal rolling mill operations, it is customary to first roll the side edges of the metallic ingots or slabs prior to their entry into the main stand of horizontally mounted rolls of a mill by means of edge rolls. These edge rolls are mounted on a vertical axis and they are located adjacent the forward or entry end of this main stand of horizontally mounted rolls. In the conventional method of operating these edge rolls it is customary to employ a set of rotatable screws mounted on a horizontal axis and connectable to the housings for the rolls. When these rotatable screws are turned they will thus bring the vertically mounted edge rolls toward or away from one another so that the distance therebetween may be adjusted depending upon the width of the ingot or slab being rolled by the edge rolls.

However, since it is necessary in some instances to broadside an ingot to the main stand of horizontally mounted rolls in the mill, i. e., to turn the ingot around sideways and then roll it to various widths on the main mill, it is also necessary to be able to operate the edge rolls with exceptional speed commensurate with the high speed at which the main mill operates. In other words, in rolling a metallic ingot or billet it is sometimes desirable to first edge roll the ingot or slab lengthwise prior to its entry into the main stand of the mill. After the ingot or slab has been edge rolled lengthwise both forward and backward, it is then necessary in order to present the ingot broadside to the mill for the edge rolls to be separated or moved apart a greater distance than that required during the period the ingot was first edge rolled lengthwise so that the ingot may then pass sideways freely between the edge rolls to the rolls of the main stand of the mill and to be able to do the same at high speeds.

The conventional screw mechanisms which have been heretofore employed for operating these edge rolls are not capable of moving the edge rolls quickly or of separating or moving the edge rolls apart at the speed with which it has been broadsided by the supporting rolls of the mill table. The reason for this is primarily because of the fact that from the point of view of design it is impractical to make screws large enough to handle the loads imposed by edging mills thereon and yet operate at high speeds.

By the apparatus of the instant invention, however, it is possible to operate the edge rolls and move them backward and forward or toward or away from one another with exceptionally high speed and at those speeds which are required in order to first edge roll the longitudinal edges of the ingot and thereafter to open the edge rolls the additional amount necessary for the ingot to be passed therebetween and supplied broadside to the main

2

mill stand in a manner consistent with the high speeds at which the horizontal rolls of the main mill operate.

This is accomplished generally by providing in an edge rolling device the combination of a plurality of laterally movable cooperating chuck elements. Edge rolls are vertically mounted within each of these chuck elements whereby when the chuck elements are moved in unison alternately toward and away from one another, the edge rolls will likewise in turn be moved laterally toward or away from one another. A primary hydraulic cylinder and piston is used for actuating each of these chuck elements and for alternately moving these chuck elements and in turn the edge rolls laterally toward and away from one another.

15 Secondary cylinders and pistons are also connected to each of the chuck elements and they operate to lock the chuck elements and the edge rolls against further lateral movement once they have been moved to a fixed rolling position at a predetermined distance apart. Means are also provided for initially adjusting the stroke of the primary pistons in their associated cylinders as well as means for retarding the flow of fluid into and out of the primary cylinders at the ends of the strokes of the pistons therein so as to dampen the thrust of the pistons at the end of each stroke thereof.

20 In addition, it is also contemplated that surge valves or analogous elements be used for operating the secondary pistons and cylinders which act to lock the chuck elements and edge rolls against lateral movement once they have been moved to their fixed rolling positions.

25 Accordingly, it is an object of this invention to provide an edging mill device having novel means for quickly and efficiently moving the edge rolls of the mill toward or away from one another.

30 It is a further object of this invention to provide an edging mill device wherein novel means are used for operating the edge rolls of the mill so as to move them toward or away from one another, together with novel means for locking the edge rolls in a fixed rolling position once they have been moved to within a predetermined distance of one another.

35 It is another object of this invention to provide an edging mill device wherein novel means are employed for locking the edge rolls of the mill in a fixed position after 40 they have been moved to within a predetermined distance of one another.

45 It is another object of this invention to provide an edging mill device wherein novel piston and cylinder means are used for moving the edge rolls toward and away from one another together with novel means for adjusting or regulating the stroke of the piston within its associated cylinder prior to the actuation thereof for bringing the edge rolls toward or away from one another.

50 It is a further object of this invention to provide a novel edge rolling device wherein hydraulically operated locking means including surge valves are used for locking the edge rolls of the device in position once they have been moved to within a predetermined distance of one another.

55 It is another object of this invention to provide novel means for damping the thrust of the piston and cylinder means used to move the edge rolls toward or away from one another at the end of each stroke of the piston.

60 These and other objects and advantages of the instant invention will become more apparent from a review of the following detailed description when taken in conjunction with the appended drawings wherein:

65 Figure 1 is a plan view partially broken of a conventional edging mill device showing the novel piston and cylinder means for actuating and moving the edge rolls of the device;

Figure 2 is a side elevational view partially in section of the edging mill device shown in Figure 1;

Figure 3 is a sectional view of the novel overall hydraulic control apparatus for actuating the edge rolls of the edging mill device and for locking the rolls in a fixed position once they have been moved to within a predetermined distance of one another including a schematic diagram of a suitable hydraulic system that may be used for operating this control apparatus;

Figure 4 is an enlarged side elevational view partially in section of the piston of the primary control cylinder together with the means for adjusting its stroke within the cylinder; and

Figure 5 is a sectional view of one type of surge valve that may be used with each of the locking or secondary cylinders and pistons.

With further reference to the drawings and particularly Figures 1 and 2, the edge rolling device of the instant invention is generally comprised of a suitable frame 1, which is mounted upon the floor of a rolling mill adjacent to the main mill stand of horizontal rolls in the rolling mill. This frame includes a pair of upright primary standard members 2 and 2' located a predetermined distance apart as indicated more particularly in Figure 1. A plurality of bridging members 3 and 4 are also used to tie standards 2 and 2' together and to bridge the gap therebetween. Members 3 and 4 also serve as horizontal guide or rail members for the carriage elements 7 and 8 which are mounted thereon.

A secondary standard member 5 is located on the top of standard 2 while a bracket member 6 is in turn fixed to the top of the opposite standard 2'. Standard 5 and bracket 6 are both rigidly mounted on their respective standards. Also disposed between the standards 2 and 2' are the carriage elements 7 and 8. A chuck member 9 is dependingly attached to the lower portion of carriage 7 and chuck member 10 is dependingly attached to the lower portion of carriage 8 in a manner well known in the art. Rotatably mounted in the chuck members 9 and 10 are the vertical edge rolls 11 and 12. Each of these edge rolls is mounted in its respective chuck member in such a way that its axis is disposed in a vertical plane.

The various carriage members 7 and 8 also serve as housings for the several gears and shafts by means of which the two edge rolls 11 and 12 are ultimately attached to a source of power so that these edge rolls may be positively driven.

The various gears and shafts, which may be disposed in a conventional manner within the housings 7 and 8 can be ultimately driven by the main drive shaft 13 connected to a suitable source of power, when drive shaft 13 is suitably coupled to the splined secondary drive shaft and guide 14 which also connects the two carriage and housing members 7 and 8. In this way also the carriages 7 and 8 may be moved on the rails 3 and 4 and along the splined shaft 14 toward or away from one another without in any way interrupting the rotation of the main drive shaft 13 and the shaft 14 which in turn directly controls the gears and other shafts, which drive the edge rolls 11 and 12.

Suitably disposed within the bottom portion of the framework 1 are a plurality of idler rolls 15 journaled in a framework 16 located approximately in the central lower portion of the edge rolling or vertical mill device. These rolls serve as the main supporting surface for the ingot or slab as it is edge rolled by rolls 11 and 12. In addition, other idler rolls 17 and 18, which also serve as supporting surfaces, are also disposed at the exit and entry end of the vertical edging mill.

Also disposed intermediate the carriages 7 and 8 at the upper portion of the edging mill and between the guide ways or bridging members 3 and 4 is a separating or spacer plate 19. Attached to the upper portion of this plate 19 is a U-shaped holder or bracket 20 to which the collar members 21 and 22 are attached. The splined

shaft 14 is inserted within each of the two collar members 21 and 22 and has located thereon the ribbed roller 23 which is disposed in turn inbetween the two collars 21 and 22.

This plate 19 together with collar members 21 and 22 serve as stop elements for the carriages 7 and 9 and serve to limit the distance that they together with the roll 11 and 12 may be moved toward one another at the center of the vertical edging mill.

The various elements of the device thus far described are all of conventional design. The novel control apparatus for actuating the chuck members 9 and 10 and the edge rolls 11 and 12 associated therewith will now be described. Since identical control devices are used for operating each chuck element and edge roll at either side of the mill, a description of one of the control devices will suffice for both.

Each control apparatus includes generally the housing 25 for the primary cylinder 26 and the piston 27 which is adapted to reciprocate therein. The cylinder 26 is directly attached to a chuck element 10 or 11 since it is rigidly mounted within the housing 25 which in turn is rigidly attached to a chuck element.

Accordingly, upon the operation of the pistons 27 within the cylinders 26, each of the chuck members can be moved toward or away from one another and they in turn will move the edge rolls toward or away from one another. In addition, the pistons 27 for each side of the mill are both adapted to operate in unison so that the movements of the rolls 11 and 12 will be synchronized one with the other.

As indicated more particularly in Figure 4, each of the pistons 27 includes a piston head 29 and a hollow internally threaded piston rod 30 attached thereto. Affixed to the one extremity of the piston rod 30 which is furthest removed from the piston head 29 is a cam element 31 the function of which will be described later. Rotatably mounted within the hollow internally threaded bore 32 of the rod 30 is a threaded shaft 33. The free end of shaft 33 is rotatably mounted within a ball race 34, located in the bearing member 35, which in turn is affixed directly to the frame member 1 by suitable means (not shown). In addition to the threaded portion 33', shaft 33 may also be provided with the intermediate threaded portion 36 to which may be applied one or more locking nuts 37 and 38 for fixing the position of the threaded shaft 33 relative to the bearing member 35. Shaft 33 is ultimately coupled to the electric motor 39 by means of the coupling member 40 and shaft 41, motor 39 being of a reversible type. It is understood of course that each of the primary pistons 27 are constructed in the aforesaid manner. Accordingly, when the motors 39 are simultaneously operated so also will be the shafts 33. Thus if the screws or threaded shafts 33 are rotated in one direction they will pull the piston rods 27 out of their cylinders. If the screws 33 are rotated in the opposite direction they will push the piston rods into their cylinders and fluid will flow from one side or the other in the cylinders 26 to obviate any voids in the cylinders. During the time the screws 33 are rotated by motors 39, each of the cam elements 31 will be made to travel upon the movement of the piston rod 30 between a pair of guides 42 and 43 best shown in Figure 4. By riding in these restraining guides 42 and 43 each small wing-like projection or cam element 31 will thus prevent the piston rod 30 from turning as their screws or threaded shafts 33 are rotated and the piston rods are moved backwards or forwards within the cylinders 26.

In this way, a simple means is provided for adjusting each piston 27 within its cylinder 26 initially and before the actuation thereof by a suitable hydraulic system to be described later. Thus, the edge rolls can be preset for the distance they are to travel toward one another in accordance with the particular width of the ingot or billet which is to be edge rolled.

Disposed on either side of the housing 25 for cylinder 26 and piston 27 are the locking or secondary cylinders and pistons 50 and 51, 52 and 53, with the pistons 51 and 53 being rigidly affixed to a chuck element and with cylinders 50 and 52 being rigidly affixed to the frame 1. These locking cylinders and pistons are used to put a hydraulic lock upon the individual chuck element associated therewith when these chuck elements have been moved together with the edge rolls toward one another to a predetermined edge rolling position by the primary actuating cylinder and piston 26 and 27.

Also attached to the head end of each of the cylinders 26 is another cam element 54, the function of which will be described later. The arrangement of a suitable hydraulic system for operating the primary and secondary cylinder and piston means will now be described.

By referring to Figure 3 it will be observed that a suitable hydraulic system will include a plurality of pumps 58 and 59 driven by a motor 60. Motor 60 is mounted upon a tank 61 from which the pumps 58 and 59 draw liquid through the lines 62 and 63 and through their respective intake ports. Pump 58 is connected by line 64 to a four-way valve 65 and pump 59 is connected through the medium of a line 66 with a similarly constructed four-way valve 67. Also disposed in the lines 64 and 66 are the relief valves 68 and 69. These in turn are also directly connected to one another by line 70 which ultimately leads back to the tank 61. Each of these valves 65 and 67 is used for actuating a primary cylinder and piston 26 and 27 connected to a chuck element located at opposite sides of the edging mill. Consequently, a description of the operation and function of the valve 67 will also suffice for the operation and function of the valve 65.

Connected to line 66 intermediate valve 69 and 67 is a line 70' which leads to the rod end of the cylinder 26. Also disposed and connected to line 70' is a decelerating valve 71 which is adapted to be actuated by the cam element 31 attached to the piston rod 27 in the manner to be described later. A line 72 is used to connect the head end of the cylinder 26 with valve 67. Disposed within line 72 is another decelerating valve 73 which is adapted to be operated by the cam element 54 rigidly attached to the casing 26' of cylinder 26 in the manner to be described later.

Valve 67 which is a solenoid operated valve, has one of the outlet ports thereof plugged, namely, port 74. This valve also is provided with a main pressure port 75, a main exhaust port 76 connected to tank 61 by line 72', and a secondary outlet port 77.

The other portion of the hydraulic system or circuit connects the cylinders 50 and 52 with a tank 80 through the medium of the surge valves 82 and 81 attached to the cylinders 50 and 52 respectively. Each of these surge valves is similarly constructed, and each is provided with an exhaust port 83 by means of which the valve is directly connected to the cylinder 50 or 52. The valve is also provided with a port 84 which is adapted to be opened and closed by a piston 85 as it is moved up and down within the surge valve assembly. In order to operate piston 85, the upper portion of the valve assembly is provided with a piston head 86 which is adapted to move within the opening 87 in the housing 88 attached to the surge valve. A compression type spring 89 is also located in opening 87 between the upper portion thereof and the piston head 86 and this spring operates to move the piston head 86 together with the disk 86' attached to the lower part of the piston 85 downwardly, thereby causing the port 84 in the valve to close. In order to actuate the piston head 86 upwardly against the action of the spring 89, a port 90 is provided in the housing 88. Thus when fluid is allowed to enter the opening 90 it acts to force the piston head 86 and piston 85 upwardly against the spring thereby raising the disk or plunger 86' of the piston 85 so that fluid can then pass freely

through the surge valves from or to the tank 80 through openings 83 and 84.

Each of pistons 85 of the surge valves 81 and 82 is operated ultimately by a pump 91 mounted on tank 61 and driven by a motor 93, with the pump receiving fluid from tank 61 at its entry port through the medium of line 94. The exhaust side of pump 91 is connected through the medium of a line 95 and relief valve 96 to a control valve 97. Control valve 97, which may be a single solenoid spring offset valve, is connected to each of the surge valves 81 and 82 through the medium of the lines 98, 99 and 100, line 99 connecting valve 81 to valve 97 and line 100 connecting valve 82 to control valve 97. Another line 101 connected to line 98 also connects control valve 97 to the surge valves which operate the secondary or locking cylinders and pistons on the other side of the edging mill.

Each of the surge valves 81 and 82 is provided with another port or opening 102. The openings 102 in valves 81 and 82 are connected through the medium of line 103 and relief valves 104 and 105 to the tank 80. Line 103 is also connected to the ports 84 of the surge valves through the medium of main branch line 106 and secondary branch lines 107 and 108.

The operation of the hydraulic system will now be described. As has been previously noted, the first thing to be determined in the operation of the hydraulic edger is the distance the edge rolls must be moved toward one another which in turn is governed by the width of the ingot or slab being edge rolled. When this is determined the screws 33 are rotated by the motors 39 in such a way that the several piston rods 27 will be actuated and moved to a predetermined fixed position within their respective cylinders 26 so that the stroke of the piston 25 will be fixed and the chuck elements and edge rolls can ultimately be moved toward one another to their proper edge rolling position.

After this initial adjustment or presetting of the primary cylinder assemblies has been made, that is, the cylinder assemblies for actuating and moving the edge rolls toward or away from one another, the next step is to operate the pistons 27 within the cylinders 26. To do this, each of the valves 65 and 67 is so adjusted that the port 77 of each valve is connected with port 75 and port 74 with port 76. At this time then, fluid will be pumped by means of the pump 59 through the lines 64, 66 and 72 and deceleration valve 73 into the head end of cylinders 26 thereby displacing the pistons 27 within cylinders 26 and causing the several chuck elements 9 and 10 together with edge rolls 11 and 12 to move a predetermined distance toward one another. As the chuck 10 for example, is moved toward chuck element 9 while fluid in the meantime of course is displaced from the rod end of the cylinder 26 through line 70' and into line 66, the deceleration valve 71, which is rigidly attached to the housing 25 to which the chuck 10 is also attached, will also move forward with the chuck element 10 and edge roll 12. Consequently, just before the end wall of cylinder 26 reaches the piston head 29, the deceleration valve 71 will be caused to be operated by the cam element 31 attached to the piston rod 27. Upon actuation, deceleration valve 71 will start to close thus preventing the cylinder 26 from slamming against the piston 27 while reducing the inertia of the moving parts. Furthermore, since the cam element 31 which operates the decelerating valve 71 is attached to the unenclosed portion of piston rod 26, the place at which valve 71 will contact the cam element 31 will also change as the position of the rod is adjusted by motor 39 thereby causing the decelerating action of the valve to occur at the proper place at all times.

While the chuck elements 9 and 10 and rolls 11 and 12 are being moved to their proper position, control valve 97 is also operated so that fluid may be passed from tank 61 through lines 95, 98, 99 and 100 to the inlet ports 90 in the surge valves. This will cause the piston heads 86

of the pistons 85 in the several surge valves to be raised against the action of the springs 89, thereby moving upward the plungers 86 attached to the lower ends of pistons 85 and opening the ports 84 in the several surge valves so that fluid can then be fed by gravity from the overhead tank 80 through the lines 103, 106, 107 and 108 to the inlet ports 84 of the surge valves and out of the valves through the outlet ports 83 into the unoccupied portions of the locking cylinders 50 and 52.

It is of course to be remembered that at this time the several piston heads 51 and 53 have in turn been moved out of the cylinders 50 and 52 or displaced therein as a result of the action of the chuck element 10 as the chuck elements are moved toward one another since these pistons are rigidly attached to this chuck element 10. Thus as these pistons 51 and 53 are moved out of the cylinders 50 and 52 respectively, fluid from tank 80 is allowed to pass into the voids left in the cylinders to fill the cylinders with fluid so that the pistons cannot recede back into their respective cylinders under the pressure exerted by the slab or ingot upon the edging rolls and in turn upon the chuck elements 9 and 10 during the time that the slab is rolled by the edge rolls 11 and 12. Thus when the surge valves are open and the cylinder 26 is moved with respect to the piston 27 as well as pistons 51 and 53 with respect to cylinders 50 and 52, the pistons 51 and 53 may be moved in and out with the rolls and fluid can flow freely in either direction through the surge valves.

At the time the solenoid valves 65 and 67 are energized, it is contemplated that the solenoid operated valve 97 will also be energized. This in turn will cause the surge valves to open and allow fluid to flow freely in either direction through the surge valves depending upon whether the cylinder 26 is moving the edge rolls toward or away from the center line of the mill. However, as soon as the solenoids of valves 65 and 67 are deenergized, it is to be understood that the valve 97 will be deenergized, thereby causing this latter valve to exhaust the control port side of the surge valves by cutting off pressure on port 90 of the surge valves, whereby ports 84 will also be closed and a hydraulic lock will be put on cylinders 50 and 52.

It is also contemplated that the surge valves 82 and 83 will also be connected to one another through the medium of the pilot ports 102, lines 102', relief valves 104, 105 and line 105', shown in dotted lines in Figure 3. During actuation of the pistons and cylinders 50, 51, 52 and 53, either one of these relief valves 104, 105 will be tightly closed. The other relief valve will be regulated to the system pressure setting. Thus in the event that either of the surge valves loses pressure through a relief valve the other surge valve will automatically pass oil or fluid back to the tank 80 thus preventing unbalanced loads between cylinders 50 and 52. It is also contemplated that the operation of the screws or threaded shafts 33 for adjusting the position of the piston rods 27 within cylinders 26 will be tied in with the control valves 65 and 67 so that at any time the motors 39 for operating the screws are energized, valves 65 and 67 will be deenergized so that the screws 33 will not have to operate against a hydraulic lock in the cylinder 26.

In order to open the hydraulic edge rolls and to separate them their maximum distance one from another so that an ingot may pass therethrough broadside to the mill after it has been edge rolled, all that is necessary is to adjust valves 65 and 67 in such a way that the ports 77 therein will be connected with the ports 76 and ports 75 with the ports 74 which are plugged. At this time, the fluid which is being displaced from the pump 59 will then pass through lines 64, 66 and 70', deceleration valve 71 and into the rod end of the cylinders 26 thereby causing pressure to be exerted upon the head of the pistons 27 so that the pistons 27 will recede within their cylinders 26 and in turn open the edge rolls. At this time also, since the cam elements 54 are rigidly attached to the

5 cylinders 26 they too will move with the cylinders and into contact with their deceleration valves 73 rigidly affixed to the frame 1. Consequently, as the cam elements 54 move into contact with the cam operated deceleration valves 73 these valves will start to close just prior to the time that the cylinders 26 reach the piston heads 29 thereby preventing the cylinders 26 from slamming against the pistons 26 as fluid is evacuated from the cylinders 26 through lines 72 and 72' to the tank 61. In addition, since the valve 97 at this time is also energized, surge valves 81 and 82 will in turn be energized and fluid within the cylinders 50 and 51 can also be displaced and forced back through the lines 107, 108 and lines 106 and 103 into the gravity feed tank 80.

10 By means of the above apparatus, the edge rolls of an edging mill can be moved forward toward one another and backwards away from one another at exceptionally high speeds. It also permits the feeding of an ingot broadside to the main stand of horizontal rolls in a mill in a relatively short time and at a speed consistent with the high speeds at which present day rolling mills operate. It is also obvious that the proposed apparatus for operating the edge rolls of an edging mill can be advantageously used under all operating conditions of an edging mill and is not limited to those instances where it is desirable to present the ingot broadside to the horizontally mounted rolls of a mill after the ingot has been first edge rolled and then leaves the edging rolls.

15 An advantageous embodiment of the invention has been herein disclosed and described. It is obvious that various changes may be made therein without departing from the spirit and scope thereof as defined by the appended claims, wherein what is claimed is:

20 1. In a rolling mill device the combination of a plurality of cooperating vertically mounted edge rolls, separate, laterally movable chuck elements for holding each of said rolls whereby when said chuck elements are moved in unison alternately toward and away from one another, said edge rolls will be moved laterally alternately toward and away from one another, means including a primary cylinder and piston for actuating each of said chuck elements and for alternately moving said chuck elements and in turn said edge rolls laterally toward and away from one another, secondary piston and cylinder means apart from said primary cylinder and piston for locking said chuck elements and said edge rolls in a fixed rolling position once they have been moved to within a predetermined distance of one another, the secondary piston of said secondary piston and cylinder means being directly connected to a chuck element and surge valve means for controlling the operation of said last mentioned piston and cylinder means.

25 2. In a rolling mill device, the combination of a plurality of cooperating vertically mounted edge rolls, separate laterally movable chuck elements for holding each of said rolls, whereby when said chuck elements are moved in unison alternately toward and away from one another said edge rolls will be moved laterally alternately toward and away from one another, cylinder and piston means for actuating said chuck elements and for alternately moving said chuck elements and in turn said edge rolls laterally alternately toward and away from one another, piston and cylinder means separate from said first mentioned cylinder and piston means for locking said chuck elements and said edge rolls in a fixed rolling position once they have moved to within a predetermined distance of each other, means for initially adjusting the stroke of the piston within the cylinder of said first mentioned piston and cylinder means prior to any actuation of said first mentioned piston and cylinder means, and surge valve means for controlling the operation of said second mentioned piston and cylinder means.

30 3. In an edging mill device, the combination of a plu-

rality of laterally adjustable cooperating chuck elements, an edge roll vertically mounted within each of said chuck elements, whereby when said chuck elements are moved in unison alternately toward and away from one another, said edge rolls in turn will be moved laterally alternately toward and away from one another, a primary cylinder and piston for actuating each of said chuck elements and for alternately moving said chuck elements and in turn said edge rolls laterally alternately toward and away from one another, a secondary piston and cylinder also operatively connected to each of said chuck elements for locking said chuck elements and said edge rolls in a fixed rolling position once they have been moved to within a predetermined distance of each other, means for initially adjusting the stroke of the primary piston in said primary cylinder prior to the actuation thereof, said means including a rotatable shaft, a piston head and a piston rod having a hollow interiorly threaded bore attached to the said piston head, and a threaded shaft, one end of which is rotatably mounted within said hollow bore in said piston rod and the other end of which is operatively connected to said rotatable shaft.

4. The combination claimed in claim 3 including fluid conduit means for operating said primary piston and cylinder and decelerating valve means in said fluid conduit means for dampening the thrust of the primary piston in said primary cylinder at the end of the strokes thereof during the actuation of the said primary piston in the said primary cylinder.

5. In an edging mill device, the combination of a plurality of laterally adjustable cooperating chuck elements, an edge roll vertically disposed within each chuck element whereby when said chuck elements are moved in unison alternately toward and away from one another, said edge rolls in turn will be moved alternately laterally toward and away from one another, a primary cylinder and piston for actuating each of said chuck elements and for moving said chuck elements and in turn said edge rolls alternately laterally toward and away from one another, piston and cylinder means separate from said primary cylinder and piston also operatively connected to each of said chuck elements for locking said chuck elements and said edge rolls in a fixed rolling position once they have been moved to within a predetermined distance of each other, means for initially adjusting the stroke of the primary piston in said primary cylinder, said means including a drive shaft, a piston rod having a hollow interiorly threaded bore, a threaded shaft having one extremity movably mounted within said hollow bore in said piston rod and the other extremity attached to said drive shaft, and power means for rotating said drive shaft and in turn said threaded shaft in alternate directions whereby said piston rod and in turn said primary piston can be moved to different predetermined positions within said primary cylinder.

6. The combination claimed in claim 5 including guide means for preventing rotation of the hollow piston rod in said primary cylinder during the initial adjustment of said primary piston therein by rotation of said threaded shaft.

7. The combination claimed in claim 5 including fluid conduit means for operating said primary piston and cylinder and decelerating valve means in said fluid conduit means for dampening the thrust of the primary piston in said primary cylinder at the ends of the strokes thereof and during the actuation of said primary piston in said primary cylinder.

8. In an edge roll device of the type described for edge rolling an ingot or the like, the combination of a plurality of laterally adjustable cooperating chuck elements, an edge roll vertically mounted within each chuck element, whereby when said chuck elements are moved in unison alternately toward and away from one another said edge rolls in turn will be moved alternately toward and

away from one another, separate primary cylinders and pistons operable in unison for actuating each of said chuck elements and for moving said chuck elements and in turn said edge rolls laterally alternately toward and away from one another, a plurality of secondary pistons and cylinders for locking said chuck elements and said edge rolls in a fixed rolling position and against lateral movement once the edge rolls have been moved to within a predetermined distance of each other, said secondary pistons being directly attached to the said chuck elements and means including a plurality of surge valves for controlling the operation of said last mentioned pistons and cylinders.

9. The combination defined in claim 8 including means for initially adjusting the stroke of the primary piston in each of said primary cylinders prior to the actuation thereof, said means comprising a piston rod having a hollow interiorly threaded bore and a threaded shaft movably mounted within the said bore in said piston rod with the threads on the shaft cooperating with the threads of the said bore in the piston rod.

10. In an edge roll device of the type described for edge rolling an ingot or the like, the combination of a plurality of laterally adjustable cooperating chuck elements, an edge roll vertically mounted within each chuck element, whereby when said chuck elements are moved in unison alternately toward and away from one another, said edge rolls in turn will be moved alternately toward and away from one another, separate primary cylinders and pistons operable in unison for actuating each of said chuck elements and for alternately moving said chuck elements and in turn said edge rolls laterally toward and away from one another, a plurality of secondary pistons and cylinders also connected to each of said chuck elements for locking said chuck elements and said edge rolls in a fixed rolling position once the edge rolls have been moved to within a predetermined distance of one another, means including surge valves for operating said second mentioned pistons and cylinders, and means for initially adjusting the stroke of the primary piston in each of said primary cylinders prior to the actuation thereof, said means including a motor element, a piston rod having a hollow interiorly threaded bore, a shaft having one threaded extremity rotatably mounted within said hollow bore in said piston rod, with the threads on the shaft cooperating with the threads of the said bore in the piston rod and with the other end of the said shaft being connected to the said motor element.

11. The combination claimed in claim 10 including guide means for preventing rotation of the primary piston in said primary cylinder during the initial adjustment of the primary piston therein by the rotation of said threaded shaft.

12. The combination claimed in claim 10 including fluid conduit means for operating said primary pistons and cylinders and decelerating valve means in said conduit means for dampening the thrust of the primary pistons in said primary cylinders at the end of the strokes thereof and during the actuation of said primary cylinders and pistons.

13. In an edge roll device of the type described for edge rolling an ingot or the like, the combination of a plurality of cooperating vertically mounted edge rolls, separate laterally movable chuck elements for holding each of said rolls, whereby when said chuck elements are moved in unison alternately toward and away from one another said edge rolls will be moved laterally alternately toward and away from one another, primary piston and cylinder means for actuating each of said chuck elements and for alternately moving said chuck elements and in turn said edge rolls laterally toward and away from one another and secondary piston and cylinder means separate from said primary cylinder and piston means for locking said chuck elements and said edge rolls in a fixed rolling position once they have been moved to within a predetermined distance of one another, the secondary pistons of said

11

secondary piston and cylinder means being directly affixed to said chuck elements.

14. The combination defined in claim 13 including fluid conduit means for operating said primary piston and cylinder means, and decelerating valve means in said fluid conduit means for dampening the thrust of a primary piston in a primary cylinder at the end of the strokes thereof during the actuation of said primary piston in said primary cylinder.

15. In an edge roll device of the type described for edge rolling an ingot or the like, the combination of a plurality of vertically mounted edge rolls, separate laterally movable chuck elements for holding each of said rolls, cylinder and piston means for actuating said chuck elements and for alternately moving said chuck elements and in turn said edge rolls laterally alternately toward and away from one another, a second piston and cylinder means separate from said first mentioned cylinder and piston means for locking said chuck elements and said edge rolls in a fixed rolling position once they have been moved to within a predetermined distance of one another, the pistons of said second mentioned piston and cylinder means being directly affixed to said chuck elements, means for initially adjusting the stroke of a piston within a cylinder of said first mentioned piston and cylinder means prior to any actuation thereof, and surge valve means for controlling the operation of said second mentioned piston and cylinder means.

16. In a rolling mill device, the combination of a plurality of cooperating vertically mounted edge rolls, separate laterally movable chuck elements for holding each of said rolls, primary cylinder and piston means for actuating said chuck elements and for alternately moving said chuck elements and in turn said edge rolls laterally alternately toward and away from one another, piston and cylinder means separate from said primary cylinder and piston means for locking said chuck elements and said edge rolls in a fixed rolling position once they have been

moved to within a predetermined distance of each other, means for initially adjusting the stroke of a piston within a cylinder of said primary piston and cylinder means prior to any actuation thereof, surge valve means for controlling the operation of said second mentioned piston and cylinder means, fluid conduit means for operating said primary piston and cylinder means, and decelerating valve means in said fluid conduit means for dampening the thrust of a primary piston in a primary cylinder at the end of the strokes thereof during the actuation of said primary piston in said primary cylinder.

17. In a rolling mill device, the combination of a plurality of cooperating vertically mounted edge rolls, separate laterally movable chuck elements for holding each of said rolls, primary cylinder and piston means for actuating said chuck elements and in turn said edge rolls, secondary piston and cylinder means separate from said primary cylinder and piston means for locking said chuck elements and said edge rolls in a fixed rolling position once they have been moved to within a predetermined distance of each other, means for initially adjusting the stroke of a piston within a cylinder of said primary piston and cylinder means prior to any actuation thereof, fluid conduit means for operating said primary piston and cylinder means, and decelerating valve means in said fluid conduit means for dampening the thrust of a primary piston in a primary cylinder at the end of the strokes thereof during the actuation of said primary piston in said primary cylinder.
